UNITED STATES PATENT OFFICE.

GROVER B. MELLUS, OF LOS ANGELES, CALIFORNIA, ASSIGNOR TO MELLUS BROS. & CO., OF LOS ANGELES, CALIFORNIA, A CORPORATION OF CALIFORNIA.

TENT.

Application filed August 28, 1924. Serial No. 734,638.

This invention relates to improvements in tents.

It is a broad primary object of the invention to provide a tent having a top with a second top disposed beneath the first top and held in spaced relation thereto so as to form a closed air space between the tops, which air space will constitute a heat insulating device which will keep the tent cool.

10 It is a further object of the invention to provide a tent having a single central support adapted to be quickly and easily taken down, collapsed and packed, which will have two tops held in spaced relation so as to provide a closed air space between them.

With the foregoing and other objects in view which will be made manifest in the following detailed description and pointed out in the appended claims, reference is had 20 to the accompanying drawings for an illustrative embodiment of the invention, where-
in:

Figure 1 is a top plan view of the improved tent,

25 Fig. 2 is a vertical section taken substantially upon the line 2—2 of Fig. 1,

Fig. 3 is a horizontal section taken substantially upon the line 3—3 of Fig. 2, and

30 Fig. 4 is a partial side elevation showing the detail of construction.

Referring to the accompanying drawings wherein similar reference characters designate similar parts throughout, the tent consists of a central upright standard or support 10 having a pointed bottom 11 which will facilitate the insertion of the support 10 into the ground. A sleeve 12 is slidably mounted upon the support 10 and is provided with a plurality of ears 13 on the exterior surface thereof. Substantially radial arms 14 are pivoted to the ears 13 by means of pins 15. The top of the support 10 is provided with a reduced extension 16 which carries a pin 17. The ends of the radial arms 14 are reduced to provide pins 18.

40 A top 19 which may be formed of canvas, khaki, or other suitable material has a central aperture 20 adapted to receive the pin 17. The edges of the top 19 are provided 45 with apertures, as at 21, which receive the pins 18 upon the radial arms 14.

50 A second top 22, which may also be formed of canvas, is provided with a central aperture 23 which is capable of receiving the reduced extension 16 of the support 10.

This second top 22 is also provided with apertures 24 around its edges which receive the pins 18. It will be noted that the second top 22 is disposed beneath the top 19 and is held in spaced relation thereto so as to form a closed air space 25. This closed or dead air space constitutes an insulating body which will keep the heat radiated by the sun upon the top of the tent from passing therethrough and into the interior of the tent.

60 Side walls 26 may be provided with apertures 27 which are also adapted to receive the pins 18 so that the side walls 26 are suspended from the ends of the radial arms 14. The bottom edges of the side walls 26 may 70 be secured to the ground as by pegs 28. A plurality of apertures 29 extend diametrically through the support 10 and are adapted to receive a pin 30 which limits the downward movement of the sleeve 12 when the 75 tent is set up.

The tent is set up as follows: The support 10 is mounted upon the ground and the sleeve 12 is raised upon the support to the desired position, whereupon the pin 30 is 80 inserted into the next lowest aperture 29. The top 22 is then placed over the extension 16 and the ends of the radial arms 14 are inserted into the apertures 24. The upper top 19 is then placed upon the pin 17 and the 85 apertures 21 are placed upon the pins 18. The side walls 26 may then be suspended from the radial arms 14. If desired, the side walls 26 may be placed upon or suspended 90 from the radial arms 14 before the edges of the top 19 are secured to the pins 18.

It is seen that I have provided a tent consisting of a central support having radial arms secured thereto, which has a top removably secured upon the support and to 95 the ends of the radial arms, and that there is a second top secured upon the support and the radial arms which is disposed beneath the first mentioned top and held in spaced relation thereto so as to form a closed in- 100 sulating air space.

It will be understood that various changes may be made in the detail of construction without departing from the spirit or scope of the invention as defined by the appended 105 claims.

I claim:

1. A tent comprising a tent pole, arms pivoted upon said tent pole, means providing shoulders adjacent the top of said pole and 110

the ends of said arms, a second shoulder formed upon the tent pole below the mentioned shoulder, a lower top having its central portion receivable upon said tent pole and adapted to be positioned upon the lower shoulder, the edges of the lower top being receivable upon the ends of said arms against the shoulders, and an upper top having its central portion receivable upon the pole against the upper shoulder and having its edges receivable upon the ends of said arms against the edges of the lower top.

2. A tent comprising a tent pole, arms pivoted upon said tent pole, means providing shoulders adjacent the top of said pole and the ends of said arms, a second shoulder

formed upon the tent pole below the mentioned shoulder, a lower top having its central portion receivable upon said tent pole and adapted to be positioned upon the lower shoulder, the edges of the lower top being receivable upon the ends of said arms against the shoulders, an upper top having its central portion receivable upon the pole against the upper shoulder and having its edges receivable upon the ends of said arms against the edges of the lower top, and side walls depending from the ends of said arms.

In testimony whereof I have signed my name to this specification.

GROVER B. MELLUS.
